UNITED STATES PATENT OFFICE.

JAMES SLATER, OF ASHTON-UNDER-LYNE, ENGLAND, ASSIGNOR TO SYDNEY MASON, OF ASHTON-UNDER-LYNE, ENGLAND.

DRAWING-MOTION OF COTTON-COMBING MACHINES.

SPECIFICATION forming part of Letters Patent No. 730,711, dated June 9, 1903.

Application filed February 1, 1902. Serial No. 92,136. (No model.)

To all whom it may concern:

Be it known that I, JAMES SLATER, foreman carder, a subject of the King of Great Britain, residing at Oxford Mills, Ashton-under-Lyne, 5 in the county of Lancaster, England, have invented new and useful Improvements in the Drawing-Motion of Cotton-Combing Machines, of which the following is a specification.

10 This invention relates to an improvement applicable to the drawing-motion at the delivery end of cotton-combing machines; and the objects of the said invention are to diminish the draft and at the same time to increase considerably the productive capacity 15 of such machines.

The manner in which my said invention is to be performed or carried into practical effect will be readily understood on reference to 20 the drawings hereunto annexed and the following explanation thereof.

On the annexed drawings, Figure 1 is a sectional view, Fig. 2 a plan view, and Fig. 3 an elevation, of part of the delivery end of a cotton-combing machine. Fig. 4 is a side elevation, and Fig. 5 is a plan, of enough of a cotton-combing machine to illustrate in what relation to the carding-rolls the drawing-rolls are placed.

25 A cotton-combing machine usually consists of a series of from six to ten "heads" A, B, and C, which are arranged along the side of a polished iron plate, along which the slivers proceed in parallel lines in the direction of the arrows, Fig. 5, toward the drawing-rollers at the delivery end of the combing-machines. Hitherto the drawing-rollers *a* have been made in one continuous length, whereby the whole number of slivers would pass through them 30 into a single trumpet *c*, then through the calendering or delivery rollers *b* into a single can—i. e., ten slivers into one can. According to my invention I divide the drawing-rollers *a* into two sections and pass only, say, four or 45 five ends or slivers through each section,

(see Fig. 5,) and each section of four or five ends passes through a separate trumpet *c* and then through the calendering or delivery rollers *b*, each four or five ends into a separate can.

50 According to the old method the speed at which the combing-machines could be worked and the slivers drawn and delivered into the coiling-cans was limited by the maximum speed at which the "coilers" could be worked; otherwise the "draft" was too great and the centrifugal force developed interfered with the "coiling" action.

I have discovered that by dividing the delivery into two sections and passing each section into a separate can running at the ordinary speed of the combing-machines could be very considerably increased and the draft diminished, thus almost doubling the "output" without deteriorating the quality 65 of the product, or instead of using one draw-box with the rollers divided into two sections, as illustrated, I may employ two draw-boxes with ordinary rollers, each provided with a separate coiler, one placed at the delivery 70 end of the combing-machine and the other at or near the center of the machine, and allow one-half of the "ends" to pass through each draw-box, so as to produce the same result.

75 I claim as my invention—

A cotton-combing machine, having its drawing-rollers divided into two sections, with a trumpet and a coiler for each section, whereby the speed of the combing-machine may be 80 increased while the draft is diminished, as and for the purpose set forth.

In testimony whereof I have signed my name to this specification in the presence of two subscribing witnesses.

JAMES SLATER.
